US0D1081140S

(12) **United States Design Patent** (10) Patent No.: **US D1,081,140 S**
(45) Date of Patent: ** Jul. 1, 2025

(54) **TOOLBOX**

(71) Applicant: **Keter Plastic Ltd.**, Herzliya (IL)

(72) Inventors: **Yaron Brunner**, Kibutz Gvat (IL);
Ayala Vardi Bougat, Kefar Veradim (IL); **Uri Parizer**, Kibbutz Hukok (IL);
Omer Menashri, Kibbutz Afikim (IL)

(73) Assignee: **KETER PLASTIC LTD.**, Herzliya (IL)

(**) Term: **15 Years**

(21) Appl. No.: **29/877,086**

(22) Filed: **Jun. 1, 2023**

Related U.S. Application Data

(62) Division of application No. 29/788,657, filed on Jul. 12, 2021, now Pat. No. Des. 1,001,499.
